UNITED STATES PATENT OFFICE

ALBERT F. FIFIELD, OF ST. CATHARINES, ONTARIO, CANADA, ASSIGNOR TO THE AMERICAN FORK & HOE COMPANY, OF CLEVELAND, OHIO, A CORPORATION OF OHIO

RAIL ANCHOR

Application filed October 26, 1928. Serial No. 315,164.

My invention relates to improvements in rail anchors and relates particularly to improvements in that type of rail anchor which is retained on a rail by virtue of its inherent 5 resiliency, and by virtue of a preliminary distortion effected upon it in placing it on the rail.

My improved anchor is of a type wherein a reach bar of spring steel is required to be 10 twisted in applying the anchor to the rail base, and which, due to its resiliency, strives to regain its normal unstressed form, effecting a severe retaining grip upon the base of the rail. The anchor is provided, moreover, 15 with a downwardly extending lug or flange at one end, engageable by a tie or other fixed abutment and which tends to slew the reach bar to contribute to the gripping of the anchor on the rail.

20 An object of my present invention is to provide an improved anchor not only operative to receive the preliminary twisting effort to provide a retaining pressure grip on the rails, but also wherein terminal jaws 25 are provided so formed, and disposed, as to remove objections to prior anchors as to placement on the rail, and maintenance in service, without adding unduly to the cost of manufacture.

30 The anchor of my present invention is adapted to be provided with rail gripping jaws for retaining the anchor on the rail base flange, which are of highly tempered steel, and therefore, resiliently maintained 35 in their position on the rail base during the various conditions required to be met in practical service.

An object of my invention is to provide 40 an improved rail anchor effective to tightly grip the rail base flanges by the effort of a twisted resilient bar underlying the rail base in an attempting to regain its normal unstressed form.

45 Another object of my invention is to provide an improved rail anchor of the aforesaid type which may be easily affixed to a rail base flange with the tools ordinarily employed by workmen who are charged with the duty of maintaining the railway equipment.

50 Other objects of my invention and the in-

vention itself will become more apparent as the following description of a certain embodiment of the invention herein illustrated, progresses reference being had in the description to the accompanying drawings illustrating the said embodiment:—

Referring to the drawings:—

Fig. 1 is a view in perspective of a rail anchor, embodying the principles of my invention, affixed to a rail base flange: 60

Fig. 2 is a perspective view of the anchor, embodying the principles of my invention, the view being taken from the opposite side of the rail, from the view of Fig. 1, the position of a tool for applying the anchors being 65 indicated;

Fig. 3 is an elevational view of the anchor of Fig. 1, taken transversely of the rail but viewing the anchor from the opposite direction, the rail being shown in section; 70

Fig. 4 is a plan view of the reach bar of Fig. 3.

Fig. 5 is an end view of the bar of Fig. 4.

Figs. 6 and 7 are perspective views of the anchor "clamping shoe" as if in place, the 75 other parts of the anchor being omitted to clearly illustrate the clamping shoe, as if in place;

Figs. 8, 9 and 10 are side elevational, plan and end elevational views, respectively, of 80 the clamping shoe of Figs. 6 and 7.

Referring now to the different figures of drawings in all of which like parts are designated by like reference characters at 1, I indicate the rail base having laterally extending flanges 2 and 3, and at 4, I show a reach bar having a hooked end 5 at one end and a spring loop 6 at the other end, the two ends of the reach bar being formed as shown and adapted to embrace the rail base flange 2 and 3, respectively, as illustrated in Figs. 1, 2 and 3.

The reach bar 4 is preferably made of a single piece of bar spring steel normally formed as illustrated in Figs. 1 to 5, inclusive with a hook 5 at one end and a loop 6 at the other end, and capable of being distorted by twisting its intermediate reach portion 7 by a twisting effort exerted at the looped end 6; a clamping shoe 29 is adapted 85 to

to hold the other end of the bar 4 to the rail base flange, the shoe being variously formed, as shown in various views of the drawings, particularly Figs. 6 to 10, inclusive, and illustrated in connection with the reach bar 4 in Figs. 1 to 3, inclusive.

The clamping shoe in the embodiment illustrated preferably comprises a rounded bar of spring steel bent substantially into the form shown wherein it comprises an intermediate spring loop 8 terminating at its ends in a pair of spaced rail flange embracing jaws 9 and 10 which are adapted to engage respectively the upper surface 11 and the bottom surface 12 of a rail base flange, at preferably longitudinally spaced points thereon, as illustrated, particularly in Figs. 1, 2, 6 and 7.

Disposed laterally of the loop 8 intermediate its end 23 and the jaw 10, there is provided a supporting shoe portion 13. The jaws 9 and 10 characterize the element 29, herein termed a "clamping shoe", as a "clamp", and the intermediate portion 13 characterizes the element as a shoe. The shoe portion 13 is adapted to be placed longitudinally parallel to and against the lateral vertical edge 14 of a rail base flange, and to fit snugly with the hook 5.

The hook 5 of the reach element 4 is positioned to embrace the shoe portion as perhaps best illustrated in Figs. 1 and 3, and the opposite end of the bar 4 is then rotated upwardly to a position where the opening 15 will project above the rail base flange 3, whereupon the end of a prying tool, such as the lever 16 may be projected inwardly toward the rail web 17 to cause its tip 18 to engage with the upper surface 19 of the rail base flange 3, as shown in Fig. 2, whereupon by a lifting effort on the handle end of the tool 16, the inner corner 22 of the depending free end 20 of the reach bar loop 6 will be lifted above the level of the top corner 21 of the rail base flange 3, whereupon the free end 20 will move inwardly under the power of the resiliency of the material of which the loop 6 is made; and because of the normal unstressed form of the loop, as best shown perhaps in Fig. 4, it will be seen that the arm comprising the free end 20 has a form wherein it extends inwardly toward the middle of the rail. The bottom surface of the free end 20 of the said loop 6 is preferably inclined to the plane of the reach portion 7, extending inwardly toward the rail web 17 and inclined upwardly, as best shown in Fig. 3.

The operation just described, namely that of lifting the free end 20 of the loop 6, accomplishes a rotational movement of the loop relative to the jaws at the other side of the anchor held by the hook 5 and comprising jaws 9 and 10 of the clamping shoe which hold the reach bar with sufficient rigidity as to accomplish a certain amount of twisting

on the reach portion 7 of the reach bar. At the same time, there is a limited amount of flexing caused in the clamping shoe 29. The loop 8 depends below the bottom surface 12 of the rail base and is adapted to engage, by its lateral surfaces exposed to view in Figs. 1 and 2, with a railway tie upon which the rail 1 rests, or against some other rigid abutment which is not longitudinally movable with the rail when the rail attempts to creep incidental to passage of trains thereover during use.

When the rail attempts to creep, it tends to carry the reach bar 4, which is rigidly secured to its base flanges, with it, but this movement is restrained by the loop 8 coming into contact with the engaged surface of the tie and the tie resists movement of the loop in a direction longitudinally of the rail; and, therefore, the hook 5, which engages with the loop 8 along the portion of its lateral surface indicated at 30, Fig. 1, is prevented from movement. Therefore, the rail is gripped on the one side by the jaws 9 and 10, and on the other side by the jaw 20 comprising a pendant end of the loop 6 and the jaw 31 comprising the upper surface of the reach bar in engagement with the bottom surface 12 of the rail base flange 3. Stresses communicated by the rail in its effort to move transversely of the engaged tie, effect slewing of the shoe carrying end of the anchor and increase the clamping effect of the anchor on the rail base flanges by wedging engagement of the shoe portion 13 of the shoe element with the vertical edge surface of one rail base flange while the upwardly extending arm of the loop 6 engages the other flange edge, being retained by the engagement of the end 20 with the rail flange.

However tightly the anchor above illustrated and described engages with the rail base flanges to prevent creeping of the rails, the anchor may be easily removed from the rail base for purposes of inspection, replacement or repair by a suitable tool engageable with the inner surface 32 of the pendant, free end 20 of the loop 6 to move it outwardly from the rail until the loop can be snapped downwardly over the lateral vertical edge 33 of the rail base flange 3. This permits the reach bar to untwist and the jaws release their hold, and the anchor can be then readily taken from the rail.

In the above description, I have employed the term "embrace" as defining the relative position of the hooked end 5 of the reach bar 4 of my improved anchor relative to the rail base flange 2 over the edge 14 of which the hooked end is placed.

I use this term in its broadest sense, even though in the preferred embodiments of my invention, as described, the forward free end of the hook may not actually engage the upper surface of the rail base flange.

Having thus described my invention in a

certain embodiment, I am aware that numerous and extensive departures may be made from the embodiments herein illustrated and described but without departing from the spirit of my invention.

5 I claim:

1. In a rail anchor, a spring steel reach bar having an intermediate portion adapted for disposition below a rail base and extending transversely thereof, provided at one end with a pair of jaws adapted to embrace one of the rail base flanges, and terminating at the other end in an upstanding, inverted loop, said loop terminating in a free end disposed for engagement with an upper surface of the opposite rail base flange only by a twisting effort imparted to the intermediate bar portion.
2. A rail anchor comprising a spring steel reach bar having an intermediate portion adapted for disposition below a rail base and extending transversely thereof, and provided at one end with a pair of interconnected jaws adapted to embrace one of the rail base flanges, and terminating at the other end in an upstanding, inverted loop, said loop terminating in a free end disposed for engagement with an upper surface of the opposite rail base flange only by a twisting effort being imparted to the intermediate bar portion, and a clamping shoe adapted for insertion between the vertical edge of the rail base flange embraced by said pair of jaws, and the portion of the bar interconnecting the jaws, said shoe comprising a portion depending below the bar and adapted for engagement by a fixed abutment such as a railway tie.
3. In a rail anchor comprising a spring steel reach bar having an intermediate portion adapted to transversely underlie a rail base and terminating at one end in a reversely turned hook, and terminating at the other end in an upstanding inverted loop, said loop terminating in a free arm adapted to effect downwardly directed pressure against an upper surface of a rail base flange, and a separate shoe element for the hooked end having an intermediate portion adapted to be disposed between the hook and the lateral surface of the rail base flange, and extending in peripheral relation with the rail, said shoe element having an end portion adapted to underlie the rail base and another pendant portion adapted for engagement with the lateral surface of a rail supporting tie.

4. In a rail anchor comprising a spring steel reach bar having an intermediate portion adapted to transversely underlie a rail base and terminating at one end in a reversely turned hook, and terminating at the other end in an upstanding inverted loop, said loop terminating in a free arm adapted for spring pressure engagement with an upper surface of a rail base flange, and a separate shoe element for the hooked end having an intermediate portion adapted to be disposed between the hook and the lateral surface of the rail base flange, and extending in peripheral relation with the rail, said shoe element having an end portion adapted to underlie the rail base and another pendant portion adapted for engagement with the lateral surface of a rail supporting tie.

50 intermediate portion adapted to be disposed between the hook and the lateral surface of the rail base flange, and extending in peripheral relation with the rail, said shoe element having end portions adapted to respectively underlie and overlie the rail base flange.

55 5. In a rail anchor comprising a spring steel reach bar having an intermediate portion adapted to transversely underlie a rail base and terminating at one end in a reversely turned hook, and terminating at the other end in an upstanding inverted loop, said loop terminating in a free arm adapted for engagement by its end with an upper surface of a rail base flange, and a separate shoe element for the hooked end having an intermediate portion adapted to be disposed between the hook and the lateral surface of the rail base flange, and extending in peripheral relation with the rail, said shoe element having end portions adapted to respectively underlie and overlie the rail base flange, and a pendant portion adapted to engage the lateral surface of a rail supporting tie.

60 6. In a rail anchor comprising a spring steel reach bar having an intermediate portion adapted to transversely underlie a rail base and terminating at one end in a reversely turned hook, and terminating at the other end in an upstanding inverted loop, said loop terminating in a free arm adapted for engagement by its end with an upper surface of a rail base flange, and a separate shoe element for the hooked end comprising a single bar of spring steel, having an intermediate portion adapted to be disposed between the hook and the lateral surface of the rail base flange, and extending in peripheral relation with the rail, said shoe element having an end portion adapted to underlie the rail base and another pendant portion adapted for engagement with the lateral surface of a rail supporting tie.

65 7. A rail anchor comprising a reach bar having an intermediate portion adapted for disposition below and transversely of a rail base and provided at one end with an upwardly extending portion adapted for engagement with a lateral surface of a rail base flange, and at the other end in an upwardly extending portion spaced from the opposite rail base flange lateral surface, and a separate jaw element comprising a spring steel bar formed with terminal hooks adapted respectively to overlie and underlie the associated rail base flange, and having an intermediate portion adapted for disposition between said spaced upturned bar portion and the lateral surface of the rail base flange.

8. A rail anchor comprising a reach bar having an intermediate portion adapted for disposition below and transversely of a rail base and provided at one end in an upwardly extending portion adapted for engagement with a lateral surface of a rail base flange,

and at the other end in an upwardly extending portion spaced from the opposite rail base flange lateral surface, and a separate jaw element comprising a spring steel bar formed with terminal hooks adapted respectively to overlie and underlie the associated rail base flange, and having an intermediate portion adapted for disposition between said spaced upturned bar portion and the lateral surface of the rail base flange, said jaw element comprising a portion pendant below said reach bar, and adapted for engagement with the lateral surface of a rail supporting tie.

15 9. In a rail anchor, a rail base flange embracing hook, a bar of spring steel extending therefrom and terminating in an inverted loop, one leg of the loop being integrally secured to an end of a reach bar portion adapted for disposition below the base of a rail and the free leg of the loop having a length so as to normally project it below the level of the outermost top surface of the rail base flange, and given a form tending normally to project its end inwardly from the vertical edge of said rail base flange, said anchor adapted to be secured to the rail base by lifting said loop free end above the outermost portions of the adjacent upper flange surface, whereby said end will snap inwardly to make resiliently maintained engagement with the upper surface of said rail base flange when the distorting pressure is removed.

10 10. In a rail anchor, a single piece of spring steel having an intermediate reach bar portion adapted for disposition transversely beneath the base of a rail and terminating at one end in a rail flange embracing hook, and at the other end in an upright inverted hook extension, the free leg of the extension being pendantly disposed in spaced relation laterally of the secured leg, and adapted to be lifted to resiliently torsionally distort the said intermediate bar portion, and being normally so formed as to spring its end inwardly to supporting engagement with a top surface portion of the rail base flange, when so lifted, said anchor comprising a more rigidly held portion engageable with portions of the vertical edge surface of the base flange over which said free leg is sprung.

15 11. In a rail anchor, a rail base flange embracing hook, a bar of spring steel extending therefrom and terminating in an inverted loop, one leg of the loop being integrally secured to an end of a reach bar portion adapted for disposition below the base of a rail and the free leg of the loop having a length so as to normally project it below the level of the outermost top surface of the rail base flange, and given a form tending normally to project its end inwardly from the vertical edge of said rail base flange, said loop adapted to be secured to the rail base by lifting said loop free end above the outermost

portions of the adjacent upper flange surface, whereby said end will snap inwardly to make resiliently maintained engagement with the upper surface of said rail base flange when the distorting pressure is removed.

12. In a rail anchor, a single piece of spring steel having an intermediate reach bar portion adapted for disposition transversely beneath the base of a rail and terminating at one end in a rail flange embracing hook, and at the other end in an upright inverted loop extension, the free leg of the extension being pendantly disposed in spaced relation laterally of the secured leg, and adapted to be lifted to resiliently torsionally distort the said intermediate bar portion, and being normally so formed as to spring its end inwardly to supporting engagement with a top surface portion of the rail base flange, when so lifted, said spring steel piece comprising a more rigidly held portion engageable with portions of the vertical edge surface of the base flange over which said free leg is sprung.

13. In a rail anchor, a metal bar terminating at one end in an upstanding reversely turned hook and at the other end in an upstanding laterally extending inverted loop, the free end of the loop adapted to be sprung into engagement with the upper edge corner of a rail base flange, and a tie engaging element pendant from the hooked end having a lateral surface adapted to bear against a side of a tie.

In testimony whereof I hereunto affix my signature.

ALBERT F. FIFIELD.
